UNITED STATES PATENT OFFICE.

EUGENE OSEGOVIC, OF BROOKLYN, NEW YORK.

SEA MINE.

Application filed June 30, 1921. Serial No. 481,491.

To all whom it may concern:

Be it known that I, EUGENE OSEGOVIC, a citizen of Italy, residing at Brooklyn, in the county of Kings and State of New York, 5 have invented certain new and useful Improvements in Sea Mines, of which the following is a specification.

The object of this invention is to provide a sea mine adapted to be submerged 10 and having within the structure means for causing detonation of explosives contained in its casing.

Another object is the means provided for causing explosion within the sealed casing 15 upon contact of extending elements with fixed objects.

A third object is in the provision of means whereby the bomb may be rendered inactive without detonating the explosives 20 carried by it.

These and other like objects are obtained by the novel construction, combination and arrangement of parts, hereinafter described and shown in the accompanying drawings, 25 forming a material part of this disclosure, and in which:—

Figure 1 is a side elevational view of a bomb, the explosion chamber being partially broken away to show the mechanism.

30 Figure 2 is a fragmental side elevational view of the cable drum frame, broken away to show the water valve chamber, and showing the valve control mechanism in released position after towing in of the mine has been 35 begun;

Figure 3 is a partial sectional, partial side elevational view of the control mechanism, the view being taken in a plane at right angles to Figure 2, and with the cable 40 checking mechanism shown in its intermediate position after the mine has been placed in the water.

Figure 4 is a bottom plan view showing the contact fingers in firing position, the 45 bottom of the casing being omitted.

Figure 5 is a fragmental side elevational view of the frame showing the automatic firing control mechanism.

Figure 6 is a similar view of the opposite 50 side of the frame showing the automatic water valve control, in locked position.

Fig. 7 is a view of the mechanism shown in Fig. 5 but with the cable checking mechanism shown in intermediate position as 55 shown in Fig. 3.

Fig. 8 is a view similar to Fig. 7, showing

the cable checking mechanism in locked position before placing the mine in the water, with members 50 and 52 and 60 removed for the sake of clearness.

60 Referring to the drawings, the numeral 10 designates a hollow conical metal casing having a domed head 11 at its lower, smaller end and a cover 12 fitted upon the larger upper end.

65 A plate 13 is secured transversely in the casing near the cover 12 forming a partition having a central circular opening closed by a disc 14, held by bolts 15.

A hub 14' formed with the disc 14, engages a flanged rotatable collar 16, its flange 16' supporting the inner ends of a plurality of contact fingers or antennæ 17, tangentially disposed and pivotally secured by pins 18, these fingers being angularly bent to 70 pass freely out through slots 20 in the upper edge of the casing 10.

75 Extending into the explosion chamber 19, adjacent the upper portion of the hub 14', is a tube 21 held by bolts 22 passing through 80 the flanged head 23 of the tube, the upper end of which is adapted to receive detonating caps 24.

85 Interiorly of the tube 21 is a firing pin 25 its stem 26 passing through the hub 14' and slidably engaging a sleeve 27 having an angular cam-like upper end, and is provided with a squared end to engage a wrench for 90 positioning the parts as in Fig. 1, that is, to lock the firing pin against action until released by moving the locking lever to allow the sleeve 27 and pin to fall.

The stem of the pin is encircled by a compression spring 32 as shown in Figure 1. A forked locking lever 30, operating between the element 27 and a sleeve 28, fixed to the stem, has an extending arm 29 engaging with the 95 detent extending from the sleeve 28 thereby holding the firing pin 25 away from the cap 24. The lever 30 operates in a slot made 100 in the hub 14' on a pin 31 which extends outwardly through the casing 10, (see Fig. 4).

105 The lever 30 normally holds apart sleeve 27 (loose on the stem 26) and sleeve 28 (rigid on said stem), as an added safety precaution in storing and moving the mine about before placing it in the water, so that, even if by accident the cocking pin 35 should be released, the lever 30 would prevent release of the sleeve 28, and hence of the 110 firing pin, 26.

Fixed to the upper portion of the stem

26 is a rigid arm 34 having at its outer end a pin 35 engageable with a raised foot 36, integral with the flange 16' and in which position the firing pin 25 is cocked or set 5 for firing as shown in Figure 1.

A notch 40, formed in the flange 16', is receptive of a locking cam 41, secured to a spindle 42, rotatable in the forked bearings 43 and 44, fixed to the partition plate 13.

10 The squared end 42' of the spindle passes through an opening in the casing 10 in a manner permitting manual operation.

Secured to the spindle 42, between the forks of the bearing 43, is an extending 15 lever arm 46, provided with an elongated slot 48 adapted to pivotally and slidably receive a pin 49 transversely connected to the end of a rod 50, the same extending through the partition plate 13 and a stuff-

20 ing box 11' in the lower closed end 11 of the casing. The rod 50 terminates in a forked end 51, within which is pivotally secured a connecting link 52, its outer end having an elongated slot 53, engaging a pivot screw

25 54 secured through the forked element of a spring actuated operating arm, generally designated by the numeral 60, to which reference will again be made and its purpose disclosed.

30 Rigidly attached to the convex surface of the casing base 11 are a pair of frame brackets 61 and 62, held in parallel spaced relation by spacing rods 63. Between the frames 61 and 62 is mounted a tubular casing 64, its larger end being secured to the inside of the frame 61, and its reduced extension 65 is supported by a hollow screw 66 passing through the frame 62.

35 Internally of the tubular casing 64 is an inner tube 67, engaging a screw threaded plug 68, having a stem 69 of reduced diameter adapted to pass through the screw 66, its projecting end being squared for adjustment.

40 45 A plunger 70 is slidable within the tube 67, its smaller end engaging a disc 71, disposed within the opening in the frame 61, and forced outward by the compression spring 72, acting between the plug 68 and the plunger 70.

A diaphragm 74, in contact with disc 71 is secured against the frame 61 by a ring 75 held by suitable fastening means.

45 50 Forks 76, fixed to the disc 71, extend outwardly through the diaphragm 74 and pivotally engage a cam 78 the same being an element of a locking arm, generally designated by the number 77, and having a parallel extension 79 pivotally engaged in a 55 slotted clip 80, fixed to the side frame 61, the opposite end 77 of the locking arm terminating in an angularly bent projection 81, forming a grip for manual operation.

55 60 A cylindrical casing 90 is rotatably mounted on a stud 92, fixed to the side frame

61, the stud having a slot 93 to retain the inner bent end of a spiral spring 94 loosely encircling the stud and having its outer end engaged in the casing 90, a nut 96 holding the arm in place. The casing 90 is 70 formed like a hollow shell of cylindrical shape, rotatable about the stud 92 and being normally urged by the spring 94 in a counter-clockwise direction (Fig. 5), thus normally tending to urge the tooth 98 (below 75 mentioned) into engagement with the gear 100 (below mentioned).

Formed upon the casing 90 are toothed 80 projections 97 and 98 to engage with a gear 100; also from said casing extends an arm 101 rigid with arm 60 provided with a transverse slot in which is rotatably mounted a roller 102 adapted to make a contact with the cam 78.

A cable drum 110, upon which is wound 85 a cable 115, is located between the upper portions of the frames 61 and 62, and is fixed to a shaft 111, one end being slotted for engagement with a pin 112, passing diametrically through the hub 113 rotatably mounted in the frame 61, and having an opening in which the shaft 111 may be moved in the manner of a universal joint, the hub 113 having its opposite end passing through an opening in the frame 61 and 90 on which is mounted the gear 100, held in place by a nut 114. Pressure of the inclined surface of the cam 78 against the roller 102, caused by the spring 72 acting thru plunger 70 and disk 71, acts as a lock to hold 100 the arm 101 in its normal position, as shown in Figs. 1 and 8, before the mine is placed in the water. Then, with the cable checking mechanism in the locked position shown in Figs. 1 and 8, the tooth 97 engages the gear 105 100 and prevents rotation of the drum 110 and paying out of the cable 115, below mentioned. As soon as the mine is placed in the water, pressure of the latter on the diaphragm 74 will cause the diaphragm to move 110 partway in against the force of the spring 72. Thus the cam 78 will be drawn away from the roller 102 and will release the latter, allowing it to move in a counter-clockwise direction owing to the force of the 115 spring 94, into the intermediate position shown in Figs. 3 and 7, in which the roller is checked from further movement by the projection 81. Then, as is apparent in Fig. 7, both teeth 97 and 98 will be free of the gear 120 100, and said gear and hence also the drum 110, will be free to rotate, which they will do owing to the weight of the mine in sinking and drifting. When the mine has sunk to a greater depth, the increased pressure on 125 the diaphragm 74 will force the latter back farther, until the projection 81 will have been withdrawn clear of the roller 102, allowing the roller to move farther in the counter-clockwise direction owing to the 130

spring 94, until the tooth 98 will engage the gear 100, thus checking further rotation of the drum and paying out of the cable 115 and keeping the mine anchored. When letting out the mine into the water, the free end of the cable 115 is secured to the boat or to any suitable anchorage, and the mine is allowed to sink and drift as above-mentioned. Or the cradle 200 may be tossed overboard before the mine, or with it, if the water is not very deep, to act as an anchorage for the mine, in which case the free end of the cable would be attached to the cradle as shown by the fragment of cable in Fig. 1. A second cable, not shown, is secured to a suitable windlass on the boat, and to the eyelets 205 on the cover 12. This is for towing-in purposes only, and it is generally cut soon after the mine has gone overboard; however, it is provided for the event that the mine may have to be brought back to the boat before being exploded.

A block 120, secured to the outer face of the frame 62 angularly with respect to the axis of the casing 10, is bored to receive a plunger 121, having a reduced rear end 122 extending through an opening formed in the outer portion of the block 120. A coiled compression spring 122' surrounds the stem 122 within the shell 120 and normally tends to draw the plunger 121 back into the shell and thus said spring normally keeps the valve mechanism releasably locked in the closed position shown in Fig. 6. The detent pin 137 acts as a check to the lever 135 by engagement with the slot 132 when the mechanism has been released and is in the position shown in Fig. 2. An elongated transverse slot 123 in the plunger 121 thus allows the cable drum shaft 111 to operate therein, the projecting portion 125 of the shaft having a squared end for manual rotation.

The plunger 121 is slotted at its opposite end to receive one end of a bell-crank lever 127, pivotally attached to the frame 62 by a screw 128, the short arm 126 of the bell-crank lever terminating in a detent 129 engageable with the end of a valve operating lever 130 projecting through a slot 131 in the frame 62.

An operating lever 135 is pivoted, as at 133, to the face of the block 120, the lever having a projecting arm 135' to which is attached a plate 136. The opposite end of the lever 135 has a shallow recess 132 engageable with a detent pin 137 fixed in the upper part of the frame 62. A connecting link 140 is pivoted at its ends to the levers 127 and 135 respectively, forming a compound lever normally held in the position shown in Figure 6 by a compression spring 142 to press the plunger block 120 outwardly. When the lever 135 is moved in a counter-clockwise direction, as will be apparent below, from its normal position as shown in

Fig. 6, it will swing the lever 127 in a clockwise direction, thus, as is obvious, releasing the lever 130 and allowing the valve 147 to open to let water into the mine.

Secured in the casing head 11 is a bushing 145 to which is attached a cover plate 146, having a conical opening forming a seat for the valve 147, the stem 148 of which passes through a guide plate 149 and engages the forked end of the lever 130, which is pivoted in a projection 150 of the plate 146 the outer end of the lever 130 being bent to extend through the slot 131 in the frame 62.

The valve 147 is held normally urged toward its open position closed by a compression spring 152 acting against the valve head and the guide plate 149. A plurality of openings 155 are provided through the bushing 145 for admitting water to the interior of the casing when the valve is raised, saturating the explosives and thereby rendering the bomb inactive.

Referring to Figure 1, the cover 12 is shown to contain a chamber 160 having an opening in the bottom through which the firing pin may be removed and adjustments affected, when the hinged cover 164 is open. Formed with the cover 164, opposite the hinge 165, is an angle catch 167 passing through a slot in the base, an opening being provided in the catch for the entrance of a bolt 166, operated by a lever 168 pivoted to a forked bracket 170 secured to the inside of the cover, the lever 168 extending outward through a slot in the base and affording means for releasing the cover 164.

It will be seen that the entire firing pin mechanism attached to the disc 14, may be removed from the casing by taking out the bolts 15, and when the disc is removed, explosives 190 may be placed in the casing.

A wheeled carriage, generally designated by the number 200, is provided on which the bomb, secured by a strap 201 held by the pin 202, may be moved about, the carriage consisting essentially of a weighted frame having curved supporting arms 203 braced by cross bars 204 on which the bomb normally rests.

In operation, the strap or band 201 being released, the bomb is entered into the sea, fully charged and assembled.

As previously mentioned, with the respective parts of the mine in the positions shown in Figures 1, 6, and 8, the rod 31 is rotated by a wrench to release the lever 30 from the sleeve 28 so that the mine may be exploded upon release of the cocking pin 35, the device is lowered into the water by means of the cable (not shown) attached to the eyelets 205. When the mine is in the water, pressure on the diaphragm 74 causes the latter to move slightly inward, allowing the roller 102 to escape from the cam 78 and to move, with the arm 101, in a counter-clockwise di-

rection (Fig. 7) into the intermediate position shown in Fig. 7, in which the roller is checked by the projection 81, and both teeth 97 and 98 are free of the gear 100, and the latter, because of the weight of the mine and the cable 115 wound on the drum 110, will be rotated as the mine drifts and sinks. When the mine has reached its proper depth, as regulated by the pressure of the spring 72, the diaphragm will be farther pushed in against the spring 72 and thus cause the roller 102 to be released from the projection 81 and to continue, with the arm 101, into the position shown in Figure 5, thus causing engagement of the tooth 98 with the gear 100 and preventing further rotation of the cable drum 110, thus anchoring the mine. Together with the shell and arm 101, the arm 60 moves in the same direction, and by means of its pivot screw 54 in engagement with the slot 53, moves the link 52 into the position shown in Fig. 5, thereby pulling the arm 50 (Fig. 3) and, thru the engagement of the pin 49 in the slot 48, turns the crank 46 and with the latter the spindle 42, in a clockwise direction (Fig. 3). Therefore, as is apparent in Fig. 4, the cam 41 is extracted from the slot 40, whence the flange 16 becomes free to rotate. If the mine then comes in contact with any solid object thru any one of the antennæ 17, the latter will turn the collar 16 about the hub 14', thus releasing the pin 35, and thru the rigid connecting element 34, the stem 26, and the latter is then forced by the spring 32 toward the cartridge 24, which is then exploded by impact of the head 25.

If, before explosion, it is desired to recover the mine, the towing cable aforementioned but not shown, is taken in, and the mine moves toward the boat. As the mine rises in the water, the weight of the water acting against the plate 136 will cause the latter to be forced in a counter-clockwise direction into the position shown in Fig. 2, against the force of the spring 122' acting thru the plunger 121, levers 127, and 140, the lever 135 rotating about the pivot 133 in the shell 120. The lever 140 being thus drawn toward the right (Fig. 2), the lever 127 will be swung in a clockwise direction, lifting its end 129 and allowing the lever 130 to swing in a clockwise direction, owing to the force of the spring 152, whence the valve 147 opens and lets water into the explosive chamber.

I claim—

1. A sea mine comprising a casing, a firing pin slidably mounted co-axial with said casing, an explosive mixture in the casing adapted to be detonated by said firing pin, a hub rigid with said casing and surrounding said firing pin, a flange rotatably mounted upon said hub, a foot integral with said flange, a cocking pin integral with said firing

pin, said cocking pin engaging said foot preparatory to firing, means urging said cocking pin against said foot, a plurality of antennæ pivotally attached to, and extending tangentially from, said flange, said antennæ being adapted, upon impact with a solid object, to rotate said flange and foot to release said cocking pin and firing pin, and manually operated safety means on said firing pin to prevent the release of the latter: a valve in the casing communicating with the explosive chamber, a flat member pivotally mounted on the casing and adapted to be partially rotated by the weight of the water during towing in of the mine, means connecting said flat member with said valve operable by partial rotation of said flat member to open said valve. 70 75 80

2. A sea mine comprising a casing, a firing pin slidably mounted co-axial with said casing, an explosive mixture in the casing adapted to be detonated by said firing pin, a hub rigid with said casing and surrounding said firing pin, a flange rotatably mounted upon said hub, a foot integral with said flange, a cocking pin integral with said firing pin, said cocking pin engaging said foot preparatory to firing, means urging said cocking pin against said foot, a plurality of antennæ pivotally attached to, and extending tangentially from, said flange, said antennæ being adapted, upon impact with a solid object, to rotate said flange and foot to release said cocking pin and firing pin, a slot in said flange, a locking cam adapted to engage said slot to prevent rotation of the flange, means for extracting said cam from said slot, and means for actuating said last-named means when the mine sinks to a predetermined depth, a valve in the casing communicating with the explosive chamber, a flat member pivotally mounted on the casing and adapted to be partially rotated by the weight of the water during towing in of the mine, means connecting said flat member with said valve operable by partial rotation of said flat member to open said valve. 90 95 100 105 110

3. A sea mine comprising a casing, a firing pin slidably mounted co-axial with said casing, an explosive mixture in the casing adapted to be detonated by said firing pin, a hub rigid with said casing and surrounding said firing pin, a flange rotatably mounted upon said hub, a foot integral with said flange, a cocking pin integral with said firing pin, said cocking pin engaging said foot preparatory to firing, means urging said cocking pin against said foot, a plurality of antennæ pivotally attached to, and extending tangentially from, said flange, said antennæ being adapted, upon impact with a solid object, to rotate said flange and foot to release said cocking pin and firing pin, a drum mounted on said casing and having a 11 12 13

cable wound thereon, a gear rigidly mounted coaxially with said drum, a rotatably mounted member adjacent said gear and having two spaced-apart teeth extending therefrom, one of said teeth being adapted to engage said gear before launching of the mine to prevent rotation of the drum, the other being adapted to engage said gear after the mine has sunk to a predetermined depth, both being adapted to lie clear of said gear during sinking or drifting of the mine, a diaphragm on the outside of the casing, resilient means urging said diaphragm outward, a spring urging said member to rotate to withdraw said first-named tooth from engagement with said gear and to bring said second-named tooth into engagement with said gear, releasable locking means to prevent rotation of said member, means on said diaphragm contacting with said last-named means, said last-named means being adapted to be partially released by withdrawal of said means on said diaphragm when said diaphragm is forced partway back by pressure of the water, a projection on said means on the diaphragm adapted to engage said releasable locking means after said partial release to prevent complete release, said first-named tooth thereby being withdrawn from engagement with said gear to allow free rotation of the drum, said projection being adapted to be withdrawn from said releasable locking means upon further backward movement of the diaphragm owing to greater pressure, said second-named tooth thereby being brought into engagement with said gear to prevent further rotation of said drum, a valve in the casing communicating with the explosive chamber, a flat member pivotally mounted on the casing and adapted to be partially rotated by the weight of the water during towing in of the mine, means connecting said flat member with said valve operable by partial rotation of said flat member to open said valve.

4. A sea mine comprising a casing, a firing pin slidably mounted co-axial with said casing, an explosive mixture in the casing adapted to be detonated by said firing pin, a hub rigid with said casing and surrounding said firing pin, a flange rotatably mounted upon said hub, a foot integral with said flange, a cocking pin integral with said firing pin, said cocking pin engaging said foot preparatory to firing, means urging said cocking pin against said foot, a plurality of antennae pivotally attached to, and extending tangentially from, said flange, said antennae being adapted, upon impact with a solid object, to rotate said flange and foot to release said cocking pin and firing pin, a drum mounted on said casing and having a cable wound thereon, a gear rigidly mounted co-axially with said drum, a rotatably mounted member adjacent said gear and having two spaced-apart teeth extending therefrom, one of said teeth being adapted to engage said gear before launching of the mine to prevent rotation of the drum, the other being adapted to engage said gear after the mine has sunk to a predetermined depth, both being adapted to lie clear of said gear during sinking or drifting of the mine,

a diaphragm on the outside of the casing, resilient means urging said diaphragm outward, a spring urging said member to rotate to withdraw said first-named tooth from engagement with said gear and to bring said second-named tooth into engagement with said gear, releasable locking means to prevent rotation of said member, means on said diaphragm contacting with said last-named means, said last-named means being adapted to be partially released by withdrawal of said means on said diaphragm when said diaphragm is forced partway back by pressure of the water, a projection on said means on the diaphragm adapted to engage said releasable locking means after said partial release to prevent complete release, said first-named tooth thereby being withdrawn from engagement with said gear to allow free rotation of the drum, said projection being adapted to be withdrawn from said releasable locking means upon further backward movement of the diaphragm owing to greater pressure, said second-named tooth thereby being brought into engagement with said gear to prevent further rotation of said drum, a valve in the casing communicating with the explosive chamber, a flat member pivotally mounted on the casing and adapted to be partially rotated by the weight of the water during towing in of the mine, means connecting said flat member with said valve operable by partial rotation of said flat member to open said valve.

5. A sea mine comprising a casing, a firing pin slidably mounted co-axial with said casing, an explosive mixture in the casing adapted to be detonated by said firing pin, a hub rigid with said casing and surrounding said firing pin, a flange rotatably mounted upon said hub, a foot integral with said flange, a cocking pin integral with said firing pin, said cocking pin engaging said foot preparatory to firing, means urging said cocking pin against said foot, a plurality of antennae pivotally attached to, and extending tangentially from, said flange, said antennae being adapted, upon impact with a solid object, to rotate said flange and foot to release said cocking pin and firing pin, a valve in the casing communicating with the explosive chamber, a flat member pivotally mounted on the casing and adapted to be partially rotated by the weight of the water during towing in of the mine, means connecting said flat member with said valve operable by partial rotation of said flat member to open said valve.

In witness whereof I affix my signature.
EUGENE OSEGOVIC.
